UNITED STATES PATENT OFFICE.

AUGUST V. POLL MILLER, OF MARCELINE, MISSOURI.

SEMAPHORE-SIGNAL.

1,328,194.

Specification of Letters Patent. Patented Jan. 13, 1920.

Application filed October 10, 1919. Serial No. 329,739.

To all whom it may concern:

Be it known that I, AUGUST V. POLL MILLER, a citizen of the United States, residing at Marceline, in the county of Linn, 5 State of Missouri, have invented a new and useful Semaphore-Signal; and I do hereby declare the following to be a full, clear, and exact description of the invention, such as will enable others skilled in the art to which 10 it appertains to make and use the same.

The invention relates to semaphore signals and has for its object to provide the standard upon which the semaphore arm is pivoted with a semi-circular plate, which 15 plate forms a background for the semaphore arm and is adapted to be painted a contrasting color to the semaphore arm, thereby increasing the visibility of the semaphore arm.

A further object is to provide a background for the semaphore signal comprising a semi-circular plate adapted to be secured by U-bolts to the semaphore standard so as to form a background of a contrasting color to the semaphore arm.

With the above and other objects in view the invention resides in the combination and arrangement of parts as hereinafter set forth shown in the drawings, described and claimed, it being understood that changes in 30 the precise embodiment of the invention may be made within the scope of what is claimed without departing from the spirit of the invention.

In the drawings:—

Figure 1 is a front elevation of the semaphore signal showing the background applied thereto.

Fig. 2 is a side elevation of the signal and background.

Fig. 3 is a detail sectional view taken on line 3—3 of Fig. 1.

Referring to the drawings, the numeral 1 designates a standard to the upper end 2 of which a semaphore arm 3 is pivoted as at 4.

The semaphore arm 3 may be controlled by any suitable mechanism through the medium of the rods 5, which are pivoted to the end 6 of the arm 3. Standard 1 is usually round, however, it is to be understood that said 50 standard may be of any shape and cross section.

The semaphore arm 3 at the present time is painted various colors to indicate various meanings; however, where the semaphore is 55 used on railroads the color of the arm may

so blend with its surroundings that it cannot be seen for a great distance; therefore, to overcome this objection a plate 7 forming a back ground is provided. Plate 7 is adapted to have its surface 8 painted a color 60 which will be a contrast to the color of the arm 3 thereby increasing the visibility of the semaphore arm 3 so that the signal may be readily seen from a distance. Plate 7 is 65 preferably semi-circular and has its central point in registration with the pivotal point 4 of the semaphore arm so that as the semaphore arm 3 is moved to various positions the background will be in registration therewith. The upper end 2 of the standard 1 is 70 painted the same color as the background so that the entire vision behind the semaphore arm 3 will be of a contrasting color. The background is secured to the standard by means of U-bolts 9 which arch the upper 75 end 2 of the standard and have their ends passing through apertures in the background and on which ends nuts 10 are threaded by means of which U-bolts and nuts the background may be securely fastened 80 to the upper end of the standard 1. To additionally secure the background 7 to the standard, rivets 11 are placed through the upper end of the standard and the background and by the use of the U-bolts in connection with the rivets it will be seen that the rivets will be prevented from splitting the standard during a high wind and also be 85 prevented from being twisted out of the same vertical plane as the semaphore arm. 90

From the above it will be seen that a background for a semaphore signal is provided which may be easily and quickly applied to a semaphore standard and one wherein, by its particular securing means, the swaying 95 of the same will be prevented and the splitting of the upper end of the standard by the rivets prevented by the use of the U-bolts.

A lamp bracket 12 is secured to the upper 100 end 2 of the standard on which bracket if so desired the lamp may be placed so as to radiate light on the background at night.

The invention having been set forth what is claimed as new and useful is:— 105

A background for semaphore signals comprising a semi-circular plate having its central point in registration with the pivotal point of the semaphore arm, said plate being painted a contrasting color to the semi- 110

phore arm, rivets passing through the semaphore standard and the background plate for securing the background plate in the same vertical plane as the semaphore arm,
5 5 U-bolts arching the upper end of the standard and having their ends passing through the background plate, and nuts threaded on the ends of the U-bolts whereby the background plate may be secured in such a manner as to prevent the splitting of the upper

end of the standard under wind pressure on the background plate.

In testimony whereof I have signed my name to this specification in the presence of two subscribing witnesses.

AUGUST V. POLL MILLER.
